UNITED STATES PATENT OFFICE

LÉON V. SOLON, OF NEW YORK, N. Y.

DESIGN FOR A GAS-BURNER UNIT

Application filed November 1, 1930. Serial No. 37,495. Term of patent 7 years.

To all whom it may concern:

Be it known that I, LÉON V. SOLON, a citizen of the United States of America, residing at New York city, in the county and State of New York, have invented a new, original, and ornamental Design for Gas-Burner Unit, of which the following is a specification, reference being had to the accompanying drawing, forming part hereof.

Figure 1 is a top plan view of a gas burner unit showing my new design;

Figure 2 is a front elevational view thereof; and

Figure 3 is a side elevational view thereof.

I claim:

The ornamental design for a gas burner unit as shown.

LÉON V. SOLON.
